US00D913654S

(12) **United States Design Patent** (10) **Patent No.:** **US D913,654 S**
(45) **Date of Patent:** ** *Mar. 23, 2021

(54) **SHOE**
(71) Applicant: **PUMA SE**, Herzogenaurach (DE)
(72) Inventor: **Daniel Dance**, Nuremberg (DE)
(73) Assignee: **PUMA SE**, Herzogenaurach (DE)
(*) Notice: This patent is subject to a terminal disclaimer.
(**) Term: **15 Years**
(21) Appl. No.: **29/687,130**
(22) Filed: **Apr. 10, 2019**

Related U.S. Application Data

(63) Continuation of application No. 29/678,171, filed on Jan. 25, 2019, now Pat. No. Des. 891,054, and a continuation of application No. 29/678,170, filed on Jan. 25, 2019, now Pat. No. Des. 891,053.

CLAIM

The ornamental design for a shoe, as shown and described.

DESCRIPTION

FIG. 1 is a top, left, and front perspective view of an ornamental design for a shoe;

FIG. 2 is a front elevational view of the shoe of FIG. 1;

FIG. 3 is a rear elevational view of the shoe of FIG. 1;

FIG. 4 is a left side elevational view of the shoe of FIG. 1;

FIG. 5 is a right side elevational view of the shoe of FIG. 1;

FIG. 6 is a top plan view of the shoe of FIG. 1; and,

FIG. 7 is a bottom plan view of the shoe of FIG. 1.

The dash-dash-dash lines are included for the purpose of illustrating portions of the shoe that form no part of the claimed design.
